TUBE BENDING TOOL

Charles B. Small, 213 Ohio St., and Anton J. Janik,
Box 94, R.D. 3, both of Elyria, Ohio

Filed July 25, 1963, Ser. No. 75,953

Term of patent 14 years

(Cl. D54—13)

Fig. 1

Fig. 2

Fig. 5

Fig. 3

Fig. 4

FIG. 1 is a side elevational view of a tube bending tool embodying our new design;

FIGS. 2, 3 and 4 are views rotated at angles of 90, 180 and 360 degrees respectively; and

FIG. 5 is an end elevational view thereof.

The dominant features of our design reside in the portions shown in full lines.

We claim:

The ornamental design for a tube bending tool, as shown and described.
